UNITED STATES PATENT OFFICE.

PEDER MIKKELSEN, OF STAMFORD, CONNECTICUT, ASSIGNOR TO THE YALE & TOWNE MANUFACTURING COMPANY, OF STAMFORD, CONNECTICUT.

DOOR-CLOSER.

1,299,373.

Specification of Letters Patent.

Patented Apr. 1, 1919.

Application filed August 26, 1918. Serial No. 251,458.

To all whom it may concern:

Be it known that I, PEDER MIKKELSEN, a citizen of the United States, and a resident of Stamford, in the county of Fairfield and State of Connecticut, have invented certain new and useful Improvements in Door-Closers; and I do hereby declare the following to be a full, clear, and exact description of the invention, such as will enable others skilled in the art to which it appertains to make and use the same.

This invention relates to improvements in door closers having means for normally holding the door in open position, and particularly to means for releasing the door holding means in the event of a fire, so that the door will automatically close and assist in preventing the spread of the fire by cutting off the draft and confining the fire to the room in which it started.

With this object in view my invention consists in the parts and combination of parts and details of construction as will be more fully explained and pointed out in the claims.

In the accompanying drawings, Figure 1 is a view in section, partly in elevation of a portion of a door closer showing my improvement applied to the same. Fig. 2 is a bottom plan view of the lever arm and the parts carried thereby. Fig. 3 is a view in transverse section through the lever arm, spring and bolt holding devices. Figs. 4 and 5 are views in plan and edge elevation respectively of the two parts of the detachable seat for the bolt head, and Figs. 6, 7 and 8 are views of the sleeve, collar and bolt.

My improvement is designed for use with door closers, or with combined checks and closers, hence I would have it understood that I do not limit its use to either, and that by the term door closer as used in the specification, I intend to include combined checks and closers.

10 represents the casing of a door closer and 11 the spindle of the same to which the lever arm 12 is secured, the said lever arm being adapted for co-operation with the mechanism of the door closer and with the door in the usual manner.

For the purpose of holding the door open, the lever arm is provided with a spring pressed dog, and the cap of the door closer with an upwardly projecting stop or rib 50 which is engaged by the lower beveled end

of the dog when the door is in its open position, the dog riding over the stop during the opening movement of the door and dropping behind the same when the door is fully open, the pressure of the spring against the dog being sufficient under normal condition to prevent the dog from rising out of contact with the stop. The dog 14 is mounted to move vertically in the arm 12, and is provided with a chisel or beveled lower end to engage the stop 13 and with a head which limits its downward movement, and against which the free end of the long flat spring 15 bears. The head of the dog may be provided with a rib formed on its top surface to enter a slot in the spring 15 so as to prevent the dog from turning in its seat, but any equivalent means may be employed for holding the flat beveled lower end of the dog in a position to properly engage the side of the stop 13.

The spring 15 is secured at one end to the lever arm 12 by a screw 17, or by a rivet if desired, with its free end in a position to bear on the head of the dog 14. Passing upwardly from the underside of the arm 12, and through the latter and also through spring 15, is the threaded bolt 18 which is locked in place by nut 19 screwed to the end of the bolt above the spring, and mounted on the head of the bolt is a collar 20 provided with a peripheral groove 21, the outer surface of the collar below the groove being preferably inclined as shown. This collar fits over the head of the bolt, and the groove in the collar forms a seat for the two part detachable seat 22 for the bolt head. The two parts of this detachable seat are preferably made of sheet brass, and each is provided with an enlarged disk shaped end 22^a and with an inwardly projecting hook shaped end 22^b. The hook shaped ends of the seat members project inwardly so as to overlap and the hooks thereon turn in opposite directions so as to interlock as shown in Fig. 1. The disk shaped ends 22^a also project inwardly so as to overlap and are secured together by a fusible alloy which will melt at a comparatively low temperature, so that in the event of a fire sufficiently close to raise the temperature up to about one hundred and fifty degrees, the alloy will melt and permit the two members of the seat to separate and thus release the bolt 18. Each member of the seat 22 is provided intermediate its ends with a curved

bearing 22^c which, when the two parts of the seat are assembled and secured together, form a circular support in which the grooved collar 20 carried on the head of the bolt rests.

5 Located intermediate the underside of the lever arm 12 and the top face of the detachable seat is the cylindrical spacing sleeve 23, the internal diameter of which is greater than the head of the bolt so that when the
10 parts of the seat 22 separate, the sleeve will be free to fall thus leaving the bolt free to be pulled upwardly by the spring 15.

In assembling the parts, the seat 22 is secured around the collar 20 and the latter applied to the head of the bolt. The bolt is then passed through the sleeve 23, lever arm 12 and spring 15, and is secured by the nut 19, the latter operating to not only regulate the tension at which the spring bears on the 20 dog, but also holds the seat and sleeve firmly in position. In the event of the proximity of heat sufficient to melt the alloy holding the two parts of the seat 22 together, the upward pull on the bolt, due to the tension of 25 the spring, will cause the two parts of the seat to be disconnected by the expanding action of the grooved collar and fall, thus releasing the spacing sleeve and permitting it to drop also. This leaves the bolt free to 30 move upwardly and release the spring thus permitting the free end of the spring to move away from the belt, or bear so lightly thereon as to be overcome by the tension of the closing spring in the door check and 35 closer. As soon therefore as the bolt is released, the spring will also be released thus removing altogether the pressure against the head of the dog or decreasing it to such an extent that it can be overcome by the tension of the closing spring 24 in the door check or closer.

It is evident that many slight changes might be resorted to in the relative arrangement of parts shown and described without 45 departing from the spirit and scope of my invention, hence I would have it understood that I do not wish to confine myself to the exact construction and arrangement of parts shown and described, but,—

50 Having fully described my invention what I claim as new and desire to secure by Letters-Patent, is:

1. The combination of a door closer having a stop, a lever arm having a longitudinally movable dog, a spring for yieldingly holding the dog in position to engage the

stop, a bolt passing through the lever arm and spring, a two part seat resting on the head of the bolt, the two parts of the seat being held together by a fusible alloy, and means resting on the said seat and bearing against the underside of the lever arm for holding the bolt against movement while the seat remains intact. 60

2. The combination of a door closer having a stop, a lever arm, a dog mounted in said lever arm, a spring secured to the lever arm and bearing on the dog, a bolt passing through the lever arm and spring, a tension adjusting nut on said bolt, a two part seat 70 the parts of which are interlocked at one end and held together by fusible alloy at the other, the said seat resting on the head of the bolt, and means interposed between the lever arm and seat and supported on the 75 latter for preventing any movement of the bolt while the seat remains intact.

3. The combination of a door closer having a stop, a lever arm, a dog mounted in the lever arm, a spring secured at one end 80 to the lever arm and resting at its free end in a position to engage the head of the dog, a bolt passing through the lever arm and spring and engaging the latter, a two part seat resting on the head of the bolt, the two 85 parts of the seat being held together by a fusible alloy and a sleeve supported by said seat and bearing against the underside of the lever arm.

4. The combination of a door closer having a stop, a lever arm, a dog carried by the lever arm, a spring secured at one end to the lever arm and bearing at its other end against the head of the dog, a bolt passing upwardly through the lever arm and spring 95 and carrying a nut for regulating the tension of the latter, a two part seat, the parts being interlocked at one end and secured by a fusible alloy at the other end, the said seat resting on the head of the bolt, and spacing means supported on the seat and bearing against the lever arm for normally holding the spring tension bolt against movement. 100

In testimony whereof, I have signed this 105 specification in the presence of two subscribing witnesses.

PEDER MIKKELSEN.
